UNITED STATES PATENT OFFICE.

HENRY D. POMIJE, OF OLIVIA, MINNESOTA

SPARKING PLUG FOR EXPLOSIVE-ENGINES.

1,086,850.

Specification of Letters Patent.

Patented Feb. 10, 1914.

Application filed February 15, 1912. Serial No. 677,794.

To all whom it may concern:

Be it known that I, HENRY D. POMIJE, a citizen of the United States, residing at Olivia, in the county of Renville and State of Minnesota, have invented certain new and useful Improvements in Sparking Plugs for Explosive-Engines; and I do hereby declare the following to be a full, clear, and exact description of the invention, such as will enable others skilled in the art to which it appertains to make and use the same.

My invention has for its object to provide an improved sparking plug for explosive engines and, to such ends, generally stated, the invention consists of the novel devices and combinations of devices hereinafter described and defined in the claim.

Hitherto sparking plugs have been provided with a plurality of sparking points of one polarity, arranged for coöperation with a single contact point or member of the opposite polarity. Also in another form of sparking plug, a spherical head operating as one electrode, has been placed within a ring used as the coöperating electrode of the plug. The former noted device has this serious defect that, if the one common electrode should become insulated or disabled by accumulation of deposits thereon, then the plug is rendered inoperative. The latter noted form of plug has no definite coöperating points, and is extremely liable to be put out of use by the accumulation of carbon deposits thereon, and by oil, which when in contact with the annular electrode, quickly covers the entire surface thereof.

In my improved sparking plug, both of the live or electrically charged members of the sparking plug are provided with a plurality of electrodes or sparking points, and the sparking points of the one member are aligned for coöperation with different sparking points of the other member. In this way, the sparking plug will remain in good operating condition as long as any one of the sparking points of one electrode is in proper condition for coöperation with a sparking point of the other electrode. This, as is evident, reduces to a minimum the possibility of the plug being disabled by accumulation of carbon or other insulating materials upon the electrodes of the sparking plugs.

The invention, in its improved form, is illustrated in the accompanying drawings,

wherein like characters indicate like parts throughout the several views.

Referring to the drawings, Figure 1 is a vertical section taken through the improved sparking plug and showing the same applied to the cylinder of an explosive engine, some parts being broken away and some parts being shown in full; Fig. 2 is a bottom plan view of the sparking plug; Fig. 3 is a horizontal section taken on the line $x^3 x^3$ of Fig. 1; and Fig. 4 is a horizontal section taken on the line $x^4 x^4$ of Fig. 1.

The numeral 1 indicates a portion of the cylinder of an explosive engine.

The improved sparking plug is made up chiefly of three main elements, 2, 3 and 4. The element 2 is a metallic socket having a threaded shank screwed through the cylinder 1 with a gas tight joint. The element 3 is an insulating sleeve, preferably of porcelain, and about one-half of which is contained within the socket 2. The lower end of the sleeve 3 is reduced in size and is formed with an exterior surface 3^a that is squared in cross section and fits a squared seat in the shank of the socket 2, see particularly Fig. 3.

The element 4 is a screw threaded metal rod that extends entirely through the insulating sleeve 3 and projects at its upper and lower ends. The central portion 4^a of the rod 4 is made square in cross section and fits a squared seat in the insulating sleeve 3.

The numeral 5 indicates a packing gland which is screwed into the socket 2 and securely holds the insulating sleeve 3 interlocked to the said socket 2.

The numeral 6 indicates a binding nut working in the threaded upper end of the rod 4.

The numeral 7 indicates a cap applied on the upper end of the sleeve 3 and through which the threaded upper end of the rod 4 is loosely passed. Working in the threaded lower end of the rod 4, but within the lower end portion of the sleeve 3, is a knurled nut 8 that bears against an internal shoulder of the said sleeve and coöperates with the nut 6 to rigidly secure the said rod 4 to the said sleeve with freedom for endwise adjustments in respect thereto. The lower or inner extremity of the rod 4 is formed with a plurality of radially projecting circumferentially spaced sparking points 9, there being, as shown, four of these. For co-

90

110

operation with the sparking points 9, the socket 2 at its inner end is provided with parallel circumferentially spaced rod like projections 10 that afford the corresponding 5 sparking points radially alined with the sparking points 9.

Inasmuch as the squared portion 3^a of the insulating sleeve 3 fits a squared seat in the socket 2, and the rod 4 has a squared portion 10 fitting a squared seat in the said sleeve 3, it is evident that, with the four sparking points 9 located ninety degrees apart and with the four sparking points or rods 10 correspondingly spaced, it is impossible to 15 put together the elements of the sparking plug without setting the coöperating sparking points 9 and 10 in proper coöperative alinement. It also follows that the said 20 sparking points cannot work out of proper coöperative alinement. By adjustments of the rod 4, the sparking points 9 may be set any desired distance within the cylinder and, in all adjustments of the said rod, the 25 sparking points 9 will maintain the proper operative relation to the sparking points or rods 10.

With the above described arrangements, it is evident that there are always four pairs of coöperating sparking points 9—10, so 30 that to render the sparking plug inoperative, all four pairs of sparking points, would have to be disabled at one time. This, of course, very greatly reduces the liability of the plug being disabled by accumulations of carbon, oil or any foreign substances resulting from explosion of gas in 35 the cylinder.

The sparking plug described, is of small cost, is easy to assemble, apply and properly 40 adjust, and is highly efficient for the purposes had in view.

It may be further added that a sparking plug to be efficient, must protrude into the cylinder to a certain point, to-wit, the

sparking points must be close to the plane 45 of the inner surface of the head of the cylinder in which it is applied. If the sparking points project too far into the center or if they do not project out of the sparking plug hole in the head of the cylinder, an 50 irregular explosion or mis-firing will be the result. The non-adjustable sparking plugs hitherto generally employed are practically only for one particular size of cylinder. My adjustable multi-sparking plug can be 55 set with its sparking points at the proper place within a cylinder of any size, and hence, is adapted for use as a sparking plug on any and all makes of automobiles or vehicles propelled by explosive engines, 60 and also, of course, the engines used for other purposes. This carries with it the additional advantage that the numerous small handlers of plugs will not be obliged to keep a stock including a large number of 65 different sizes of sparking plugs.

What I claim is:

In a sparking plug, two metallic members insulated from each other and the one extended axially through the other, the outer 70 member having a plurality of sparking points formed by metallic rods projecting therefrom parallel to each other and parallel to the axis of the plug, and the inner member having a plurality of sparking points 75 for coöperation with the said rods, and the said inner member and its sparking points being axially adjustable so as to materially change the projection of the operative portions of the points from the body of the 80 plug.

In testimony whereof I affix my signature in presence of two witnesses.

HENRY D. POMIJE.
